UNITED STATES PATENT OFFICE.

THEODORE HOLT, OF LEXINGTON, TEXAS.

PLOW-GAGE.

SPECIFICATION forming part of Letters Patent No. 285,264, dated September 18, 1883.

Application filed June 9, 1883. (No model.)

To all whom it may concern:

Be it known that I, THEODORE HOLT, of Lexington, in the county of Lee and State of Texas, have invented a new and Improved 5 Plow-Gage, of which the following is a full, clear, and exact description.

The invention will first be described in connection with the drawings, and then pointed out in the claims.

10 Reference is to be had to the accompanying drawings, forming a part of this specification, in which similar letters of reference indicate corresponding parts in all the figures.

Figure 1 is a broken rear perspective view 15 of a plow with my improved gage attached. Fig. 2 is a partly-sectional side elevation thereof, and Fig. 3 is a perspective view of a guide-block employed in connecting the plow mold-board and the lower slide-plate of the 20 gage to the plow-stock.

a represents the plow-beam, having any 25 approved handles, b b, and stock c, to which stock the plowshare or cultivator-shovel d is attached at its foot by a bolt, e, which holds the shovel d in a recess of the face of stock c, so that a shoulder, e', thereof takes the thrust 30 of the work. The fastening-bolt e passes through the stock c, and through an aperture, f', of a metal block, f, which I place in a recess, g, at the back and lower end of stock c, as in Fig. 2. This block f not only shields 35 the stock from the wear of the nut e' of bolt e, but by its outer longitudinal rib or projection, h, forms shoulders i at each side, against which the edges of a slot, k', of the lower connecting-plate, k, of the gage-shoe l slide, to 40 form a guide to and lateral support for plate k, which is of a thickness slightly less than the rib h of block f, so that the overlapping nut e' of bolt e may be tightened without binding the plate k fast to the stock c, to which plate k may be tightened by an upper bolt, m, and nut m', to secure the forward end of shoe l at proper 45 level or height to suit the style of plowshare with which the gage is used. I prefer to make the gage-shoe l in wedge form, or thinner vertically at the front, where I connect the shoe to the plate k by any suitable hinge-joint, n, which will allow the free swing in vertical 50 plane of the rear end of the shoe l, which end I connect to the stock c by a bent bar or plate,

o, held to the stock adjustably by a bolt, p, which passes through the stock c, and a guide-block, q, secured thereon, which block q fits the slot o' of plate o loosely, for guiding the 55 plate, which may be firmly locked to stock c by the nut r, fitted to the threads of bolt p.

In operation, should it be desired to substitute the plowshare d by another one, or to adjust the shoe l for gaging the working depth 60 of the plow in the soil, the bolts m p are loosened, and the plates k o can then be raised or lowered on stock c to suit the plow in use or the varying conditions of the soil, and when properly adjusted the bolts m p may be again 65 tightened to hold the shoe l firmly in place to steady the plow and hold it evenly to its work, to the great relief of the plowman and of the horses, as the plow will not dip in sandy or loose soils, and the draft-strain will be materially lessened because of the uniform depth of 70 furrow cut by the plow.

It will be noted that the gage may be adjusted as desired without loosening the connection of the share d with the plow-stock, and 75 when it is desired to shift or change the stock, it may readily be done by running off nut r, and swinging the bar o and shoe l forward on the hinge n and entirely free from the bolt-connections e e' f of the plowshare. 80

My improvement is thus simple and cheap to construct, and is durable and effective in operation, making all kinds of cultivating 85 plows more desirable and handy in use.

Having thus fully described my invention, I 85 claim as new and desire to secure by Letters Patent—

1. The block f, arranged in a recess, g, having a rib or projection, h, and provided with side shoulders, i, in combination with the stock 90 c and slotted plate k, whereby the block forms a guide and lateral support to the plate, as described.

2. The adjustable bent bar o and the adjustable bar k, combined with the hinged shoe 95 l, stock c, and guide-block f, as shown and described.

THEODORE HOLT.
